UNITED STATES PATENT OFFICE.

MATTI WAINOLA, OF NEW YORK, N. Y.

SHIP'S BERTH.

1,149,100.

Specification of Letters Patent.

Patented Aug. 3, 1915.

Application filed February 20, 1915. Serial No. 9,705.

To all whom it may concern:

Be it known that I, MATTI WAINOLA, a subject of the Czar of Russia, residing at New York, in the county of New York and State of New York, have invented new and useful Improvements in Ships' Berths, of which the following is a specification.

This invention relates to ships' berths and it consists in the novel features hereinafter 10 described and claimed.

The present invention is an improvement over the structure shown in my prior application for patent for ship's berth, filed October 17, 1914, Serial No. 867,169.

An object of the invention is to provide 15 simple and efficient means for permitting the mattress frame of the berth to have movement with relation to the supporting base thereof whereby the mattress frame will remain approximately horizontal while the vessel or ship to which the berth is applied is rocking or rolling.

With this object in view the berth includes 20 a supporting base having a standard mounted thereon which slidably receives a bar. A mattress frame is pivotally mounted upon the upper end of the bar at a point approximately the center of the mattress frame. Bellows sections are provided and connected 25 one with the base and the other with the mattress frame and the inner edges of the said bellows sections are connected with a bellows frame which in turn is resiliently connected with the standard. The bellows 30 sections are adapted to retain a column of water which serves as the medium for supporting the mattress frame in a horizontal position, while the other parts of the berth follow the movement of the vessel.

In the accompanying drawings, Figure 1 35 is a side elevation of the berth with parts in section. Fig. 2 is a top plan view of the same with parts removed the said view being taken on the line 2—2 of Fig. 1. Fig. 3 is a 40 side elevation showing the berth mounted upon supporting legs.

The berth comprises a base 1 which may be mounted directly upon the surface of a deck as indicated in Fig. 1 or which may be 45 supported upon legs 2 as shown in Fig. 3. The base 1 is provided at one end with a valved water outlet 3 and a hollow standard 4 is mounted at the central portion of the base 1. The base 1 is provided at its central 50 portion with an opening which is normally closed by a plug 5 (see Fig. 1) the said

opening communicating with the interior of the standard 4. Braces 6 connect the upper portion of the standard with intermediate portions of the base 1 and retain the said 60 parts in proper position with relation to each other. A bellows section 7 is secured at its lower edge to the edge portion of the base 1 and the upper edge of the said section 7 is secured to a bellows frame 8. A bellows 65 section 9 is secured at its lower edge to the frame 8 and the upper edge of the said section 9 is secured to the edge portion of a mattress frame 10. The bottom of the frame 10 is provided with a hole 11 (see 70 Fig. 1) which is normally closed by a detachable cap 12. The mattress frame 10 is provided with a valved water inlet pipe 13 the inner end of which communicates with the space bounded by the bellows section 9. 75 Eyes 14 are provided at the upper end of the standard 4 and eyes 15 are provided at the inner edges of the sides of the bellows frame 8. Wires or rods 16 are connected at their outer end with the eyes 15 and at their 80 inner ends with the eyes 14. The said rods or wires 16 are made in sections and the said sections are joined together by means of turn buckles 17 and the said buckles may be used for lengthening or shortening the said 85 wires or rods in the usual manner. Each wire or rod 16 is provided with a coil 18 which renders the same flexible and longitudinally extensible. The bellows sections 7 and 9 are each provided with a water-proof 90 lining indicated at 19 and the said lining may be formed from any suitable flexible material.

A plate 20 is provided at the under side of the bottom of the mattress frame 10 and the 95 said plate is provided at a point between its ends with a downwardly disposed socket 21, which pivotally receives a ball 22. After the ball 22 has been inserted in the socket 21 the upper end thereof is closed by means of 100 a cap 23. A bar 24 is fixed to the ball 22 and extends down through the lower outlet of the socket 21 and is slidably received in the upper portion of the standard 4. A plunger 25 is screw-threaded upon or otherwise secured at the lower end of the bar 24 105 and is slidably received in the hollow of the standard 4 as best shown in Fig. 1 of the drawing.

The parts of the berth are assembled in 110 the following manner: The bar 24 is passed through the socket 21 and the plate 20 is

then applied to the under side of the mattress frame 10 after the cap 23 has been put in position over the ball 22. The frame 10 is then secured to the upper edge of the 5 bellows section 9. The lower end of the bar 24 is passed through the upper end of the standard and the lower end of the bar 24 is projected through the opening which is normally closed by the plug 5. The plunger 25 10 is then attached to the lower end of the bar 24 and the bar 24 is moved in an upward direction whereby the plunger 25 is carried into the upper intermediate portion of the standard 4. The plug 5 is then inserted in 15 the opening in the base 1. Water is then pumped or forced into the interior of the bellows sections through the water inlet 13 until the mattress frame 10 rests upon the surface of the water or upon a cushion of air 20 which is confined between the surface of the water and the underside of the frame 10. When the frame 10 is thus supported it will remain approximately in a horizontal position while the ship to which the berth is applied is rocking or rolling. At the same 25 time the frame 10 may have vertical movement with relation to the base 1 inasmuch as the bar 24 may slide vertically in the upper portion of the standard 25. When desired 30 water contained within the bellows sections may be drawn off therefrom through the water outlet 3. When it is desired to repair or adjust the parts contained within the bellows sections 7 and 9 the cap 12 may be 35 removed and thus an opening is provided through which the arm of an operator may be inserted for the purpose of adjusting the parts or detaching the same. As the vessel to which the base 1 is applied rolls or rocks 40 the mattress frame 10 will remain approximately horizontal and the said frame may have limited vertical movement with relation to the base 1 inasmuch as the bar 24 is guided in the standard 4. However the said 45 bar 24 in the standard 4 will prevent relative lateral movement of the intermediate portions of the mattress frame 10 and base 1.

By reason of the fact that the bellows frame 8 is connected with the inner edge 50 portions of the bellows sections 7 and 9 the said frame braces the inner portions of the said sections and prevents them from bulging in an outward direction to too great an extent. At the same time the coils 18 of the 55 members 16 may expand or contract and permit bodily movement of the frame 8 in order that the parts of the berth may have their desired relative movements to compensate for the movement of the vessel and sustain 60 the mattress frame 10 approximately in a horizontal position.

From the above description taken in conjunction with the accompanying drawing it

will be seen that simple and efficient means is provided for sustaining the mattress frame 65 approximately in a horizontal position while the vessel is rocking and rolling.

Having described the invention what is claimed is:

1. A berth comprising a base and a frame, 70 bellows sections connected with the base and the frame, a bellows frame connected with the inner portions of the bellows sections and resilient members connected with the bellows frame and the base. 75

2. A berth comprising a base and a frame, bellows sections connected with the base and the frame, a standard mounted upon the base, a bellows frame connected with the inner portions of the bellows sections and 80 longitudinally extensible members connected with the standard and the bellows frame. 85

3. A berth comprising a base and a frame, bellows sections connected with the base and the frame, a bellows frame connected with 90 the inner portions of the bellows sections, a standard mounted upon the base, longitudinally extensible members connected with the standard and the bellows frame the said members being provided at points between their ends with resilient coils. 95

4. A berth comprising a base and a frame, means for confining a column of water between the base and the frame, a guide carried by the base and a member pivotally connected with the frame and slidably received in the guide. 100

5. A berth comprising a base and a frame, means for confining a column of water between the base and the frame, a standard 105 mounted upon the base, a bar pivotally connected with the frame and slidably received in the standard.

6. A berth comprising a base and a frame, means for confining a column of water between the base and the frame, a standard mounted upon the base, a bar pivotally connected with the frame and slidably received in the standard and a plunger connected 110 with the bar and having limited movement within the standard. 115

7. A berth comprising a base and a frame, means for confining a column of water between the base and the frame, a standard mounted upon the base, a bar slidably mounted for limited movement in the standard, a ball carried at the upper end of the bar and a plate connected with the frame and having a socket which pivotally receives the ball. 120

In testimony whereof I affix my signature in presence of two witnesses.

MATTI WAINOLA.
